(57) **CLAIM**

We claim, the ornamental design for a pull, as shown and described.

DESCRIPTION

FIG. 1 is a front elevational view of the pull of the present invention; and, FIG. 2 is a right side elevational view shown in partial cross-section, wherein the cross-section is taken substantially along lines 2—2 of FIG. 1.

The threaded opening portion of the stem is shown in phantom for illustrative purposes only and forms no part of the claimed design.
